United States Patent Office.

ABNER H. BRYANT, OF PHILADELPHIA, PENNSYLVANIA.

Letters Patent No. 91,516, dated June 22, 1869; antedated June 8, 1869.

IMPROVEMENT IN POCKETS FOR EGG-CARRIERS.

The Schedule referred to in these Letters Patent and making part of the same.

To all whom it may concern:

Be it known that I, ABNER H. BRYANT, of Philadelphia, in the county of Philadelphia, and State of Pennsylvania, have invented a new and valuable Improvement in Pockets for Egg-Carriers; and I do hereby declare that the following is a full, clear, and exact description of the construction and operation of the same, reference being had to the annexed drawings, making a part of this specification, and to the letters and figures of reference marked thereon.

Figure 1 of the drawings is a side view of my pockets;

Figure 2 is a front view thereof; and

Figure 3 is a view of two strips of cloth, with gores cut out preparatory to sewing.

My invention relates to devices for transporting eggs, and is designed to accompany and be used in connection with my egg-carrier, for which Letters Patent of the United States were issued to me, under date of March 17, 1868, and September 1, 1868; and

The object of my invention is to secure greater economy in the manufacture of the pockets for said egg-carrier than has heretofore been practised.

The letter A of the drawings represents two strips of cloth, of about three inches and three-eighths of an inch in width, one strip underlying the other, the width always to correspond to the size of the pocket I desire to manufacture.

After these two strips of cloth are adjusted, in the manner mentioned, I cut out a gore, as represented, at the point a.

These gores are cut while the two strips of cloth lie

smoothly upon the table, or they may be folded over at the proper points, and the gores formed by cutting off the corners of the folded fabrics.

After these gores are formed, I fold the strips of cloth in such manner that the lower points of the gores shall touch each other, or, in other words, I place the point c of the right-hand gore over the point c of the next gore to the left, and pass the cloth, thus folded, to the machine for sewing.

The sewing is done on a line commencing at the point h of the gore, and extending diagonally across the cloth, on an angle of about forty degrees with the edge of the same.

When this process is completed, the pocket has assumed the form shown on fig. 2, and is ready for use.

The method above described secures great economy of labor and materials, and is of great value to parties engaged in the manufacture of my egg-carriers, patented as aforesaid.

What I claim as my invention, and desire to secure by Letters Patent, is—

A pocket, constructed in the manner herein described and shown, to accompany and be used with devices for transporting eggs.

In testimony that I claim the above, I have hereunto subscribed my name, in the presence of two witnesses.

ABNER H. BRYANT.
